UNITED STATES PATENT OFFICE.

FRANK R. PACKHAM AND GEORGE P. OATES, OF SPRINGFIELD, OHIO,
ASSIGNORS TO AMERICAN SEEDING MACHINE COMPANY, OF JER-
SEY CITY, NEW JERSEY, A CORPORATION OF NEW JERSEY.

AXLE FOR GRAIN-DRILLS.

No. 807,576.

Specification of Letters Patent.

Patented Dec. 19, 1905.

Application filed November 6, 1905. Serial No. 285,956.

To all whom it may concern:

Be it known that we, FRANK R. PACKHAM and GEORGE P. OATES, citizens of the United States, residing at Springfield, in the county 5 of Clark and State of Ohio, have invented certain new and useful Improvements in Axles for Grain-Drills, of which the following is a specification.

Our invention relates to grain-drills, and 10 particularly to the arrangement of the carrying-wheels and axle therefor. It is desirable in such machines to give pitch to the wheels—that is, to arrange them flaring, separated by less distance at the bottom than at the top— 15 in order to obviate the tendency of the wheels to spring inward against the grain-box under stress of heavy loads. It is also desirable to cause the wheels to “gather”—i. e., approach slightly nearer together at their forward edges 20 than at the rear edges—which tends to lighten the draft.

To provide a cheap simple form of axle embodying the above features, the principal parts of which shall be interchangeable for 25 different widths of machines, is the object of the present invention. Inasmuch as the grain-feeding devices are driven from the axle of the carrying-wheels, it is desirable that the angularly-arranged portions of the axle be 30 rotated in unison.

With the above primary and other incidental objects in view the invention consists of the construction, parts, combination thereof, or their equivalents hereinafter described, 35 and set forth in the claims.

In the drawings, Figure 1 is a view of a portion of a grain-drill, showing the inclined axle, the hub of the carrying-wheel, the grain-box, and seed-feeding devices and their actuating mechanism. Fig. 2 is an elevation showing the bed-beam and the method of connecting the inclined portion of the axle to form the continuous or arched axle hereinafter described. Figs. 3 and 4 are details of the 45 universal connection between the inclined portions and the intermediate portions of the axle; and Fig. 5 is an end view, somewhat diagrammatic, showing the direction of inclination of the axle from the vertical and horizontal. 50

Like parts are indicated by similar characters of reference throughout the several views.

Referring to Fig. 1, α represents the grain-

box; α' , the bed-rail of the supporting-frame; α^2 , the side rail. α^3 α^3 are seed-feeding devices. 55 α^4 is the actuating-shaft common to all said seed-feeding devices. α^5 is a beveled gear on said shaft α^4 , driven by a pinion α^6 on the counter-shaft α^7 , as hereinafter described. Journaled in the boxing b and pendent hanger b' , secured on the frame of the machine, is an inclined shaft b^2 , which is secured by the usual ratchet mechanism with the hub b^3 of the carrying-wheel in such manner that it will rotate 60 with said wheel. 65

It is to be understood that the shafts b^2 , inclined in opposite directions from or near the center, are located at opposite sides of the machine, as shown in Fig. 2. The direction of inclination of the shaft b^2 is downward and 70 to a less degree forward, as illustrated in Fig. 5, in which the vertical and horizontal are indicated by the dot-and-dash lines, while the arrow indicates the direction of inclination.

Mounted on the inclined shaft b^2 is a gear-disk b^4 , meshing with the adjustable pinion b^5 on the counter-shaft α^7 . The counter-shaft α^7 is supported at right angles to the shaft b^2 in suitable bearings in the bearing-box b and a hanger b^6 , secured to the grain-box. To the 80 inner ends of the respective inclined shafts b^2 are secured, by set-screws c' , couplings c , having in an extension c^2 a rectangular flaring opening c^3 . The side walls of said opening are formed convex in a longitudinal direction, as shown in Fig. 4. This coupling forms 85 a universal joint between the inclined shafts b^2 and an intermediate square shaft c^4 .

In adapting the construction to machines of different widths the same inclined shafts b^2 90 and accessories are used in machines of all sizes, the difference in width being compensated for by a longer or shorter intermediate square shaft c^4 . When used with machines of extreme width, it is desirable to provide a 95 gear-disk b^4 , counter-shaft α^7 , and pinions b^5 α^5 α^6 in connection with each of the inclined shafts b^2 at opposite sides of the machine.

It will be seen that there is thus provided a continuous revoluble arched axle which will 100 be cheap and efficient, giving to the carrying-wheels both “pitch” and “gather,” and which is easily adapted to machines of various widths.

Having thus described our invention, we 105 claim—

1. In a grain-drill, the combination, with

a supporting-frame, seedbox and carrying-wheels, of independent revoluble axles for said carrying-wheels inclined forwardly and downwardly, an intermediate shaft between said 5 revoluble axles, and universal connections between said intermediate shaft and each of said revoluble axles, substantially as specified.

2. In a grain-drill, the combination, with a supporting-frame, seedbox and carrying-wheels, of seed-feeding devices, a common shaft for said seed-feeding devices, independent axles for said carrying-wheels inclined forwardly and downwardly, a gear-disk carried on one of said inclined axles, a counter-shaft 10 arranged at right angles to said inclined shaft, a pinion on said counter-shaft engaging said gear-disk, and driving connections between said counter-shaft and the common shaft of 15

said seed-feeding devices, substantially as specified.

3. In a grain-drill, the combination, with a supporting-frame, seedbox, seed-feeding devices and carrying-wheels, of an arched revoluble axle comprising an intermediate horizontal portion, and portions inclined downwardly and forwardly, and universal couplings between said intermediate portions and end portions, substantially as specified.

In testimony whereof we have hereunto set our hands this 26th day of October, A. D. 1905. 30

FRANK R. PACKHAM.
GEORGE P. OATES.
